US0D1032287S

(12) **United States Design Patent** (10) **Patent No.:** **US D1,032,287 S**
(45) **Date of Patent:** **** Jun. 25, 2024**

(54) **STORAGE CONTAINER COVER**

(71) Applicant: **Zhejiang Shengli Plastic Co., Ltd.**,
Taizhou (CN)

(72) Inventor: **Shengli Feng**, Taizhou (CN)

(73) Assignee: **Zhejiang Shengli Plastic Co., Ltd.**,
Taizhou (CN)

(**) Term: **15 Years**

(21) Appl. No.: **29/850,725**

(22) Filed: **Aug. 23, 2022**

(51) **LOC (14) Cl.** **07-02**

(52) **U.S. Cl.**

USPC **D7/391; D9/436**

(58) **Field of Classification Search**

(57) **CLAIM**

The ornamental design for a storage container cover, as shown and described.

DESCRIPTION

FIG. 1 is a perspective view of a storage container cover, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
